Attorney

UNITED STATES PATENT OFFICE.

WILLIAM CARLETON STARKEY, OF INDIANAPOLIS, INDIANA, ASSIGNOR TO L. G. S. DEVICES CORPORATION, OF INDIANAPOLIS, INDIANA, A CORPORATION OF INDIANA.

STARTER FOR AUTOMOBILES.

Original application filed May 16, 1925, Serial No. 30,762. Divided and this application filed March 15, 1926. Serial No. 94,728.

It is the object of my invention to provide a simple and efficient starting drive for an internal combustion engine, as of an automobile.

More specifically, it is the object of my invention to provide between a starter motor and such an engine a releasable drive which will eliminate strains incident to drives now in common use, by producing a releasable meshing of the motor-driven pinion with a gear on the engine shaft before the motor has gained momentum; which will permit the free overrunning of the motor-driven pinion when the engine starts in operation under its own power, until the motor-driven pinion is de-meshed from the engine gear; and which desirably will permit a release of the drive upon excess stress even in the driving direction, so that if a backfire of the engine occurs the starter motor may continue to rotate in its normal or forward direction and thus the strain which is ordinarily put upon the starter motor and other parts upon a backfire is eliminated.

In attaining these objects, I mount on a shaft driven by the starter motor an axially shiftable pinion which by its axial movement may be meshed with and de-meshed from a gear on the engine; and provide this pinion as part of a unit which is shiftable in its entirety along the starter-motor-driven shaft and which preferably embodies a special form of coiled-spring clutch which transmits power from the starter-motor-driven shaft to the pinion in one direction while permitting free overrunning of the pinion when necessary; and desirably make this coiled-spring clutch of such character that the stress which it transmits even in one direction from

the starter-motor-driven shaft to the pinion is limited in amount, so that when such stress tends to exceed that amount the clutch releases itself and permits free relative rotation of the pinion and the starter-motor-driven shaft even in the direction in which the driving stress is normally transmitted.

The unit consisting of the pinion and the member splined on the starter-motor-driven shaft is desirably interassociated with the starter-motor switch so that the movement

of the switch shifts such unit. The starter-motor switch is so arranged that such shifting normally occurs to produce meshing of the starter-motor-driven pinion and engine gear before the starter-motor-shaft is closed; 55 but allows the closing of the switch first if the teeth of such pinion and gear at any time happen to be so nearly in direct alinement that the pinion teeth cannot enter the spaces between the gear teeth, as sometimes occurs. 60

I prefer to employ the form of clutch illustrated and described to connect together the pinion and the members splined on the starter-motor-driven shaft, but this particular form of clutch is not essential to my present 65 invention in its broader aspect. The particular form of coil-spring clutch illustrated and described in this application forms the subject-matter of the claims of my co-pending patent application Serial No. 30,762, filed 70 May 16, 1925, Patent No. 1,617,775, of which this application is a division.

The accompanying drawing illustrates my invention: Fig. 1 is a side elevation of a starting drive embodying my invention, some of the parts being broken away or in section in order better to illustrate the construction; Fig. 2 is an enlarged longitudinal section through the drive itself, to show the coiled-spring clutch and the associated parts; Fig. 75 80 3 is a section on the line 3—3 of Fig. 2; Fig. 4 is an elevation of the coiled spring of the clutch; Fig. 5 is a longitudinal section similar to Fig. 4, with a coiled spring of material of smaller cross-section, by reason of which 85 slipping may occur on excess load even in the direction in which power is normally transmitted; and Fig. 6 is a sectional detail of the shifter switch.

The engine 10 may have the usual fly-wheel 90 11, on which is the usual ring-gear 12. The engine 10 may be any type of internal combustion engine; it is shown as an automobile engine, associated with a well-known type of transmission device 13, controlled by pedals 95 14 which project through the floor board 15 of the driver's compartment of the automobile.

The starter motor 16 may also be of any suitable or convenient construction, and is 100

supplied with current from a battery 17, as is common practice. The shaft 18 of the starter motor is mounted in the usual bearings, including a bearing 19 from which such 5 shaft projects, toward the rear as shown, to carry my improved drive unit. This drive unit is desirably mounted directly on the starter-motor shaft, without intervening gearing; but it is not essential that there be 10 no intervening gearing between the starter motor and the starter-motor-driven shaft which carries my drive unit. The bearing 19 may also serve as a limit-stop to limit the movement in one direction of the drive unit 15 along the shaft 18.

The engine and starter motor, per se, may be of any standard or desirable construction.

On the projecting end of the starter-motor-driven shaft 18 I mount my improved drive 20 unit. This consists fundamentally of two parts 20 and 21, which may move together axially as a unit, but under some circumstances are fixed relatively to each other to rotate together as a unit while under other circumstances they may rotate relatively to each other.

The member 20 is loose on the starter-motor-driven shaft 18, so that it is free both 30 to slide thereon and to rotate thereon. This member 20 is provided with pinion teeth 22 which may co-operate with the teeth of the ring-gear 12. Under normal conditions the pinion 22 is in the position shown in full lines in Fig. 2, so that it is out of the plane of the ring-gear 12 and so is de-meshed therefrom. When the drive-unit 20-21 is shifted forward 35 on the shaft 18, however, the pinion teeth 22 are brought into mesh with the teeth of the ring-gear 12, as is indicated in dotted lines in Fig. 2; the bearing 19 may serve as a limit-stop to limit this forward movement of the drive unit. The forward ends of the pinion teeth 22 are desirably beveled, to facilitate 40 meshing with the teeth of the ring-gear 12, and the entrance ends of the ring-gear teeth 45 may be similarly beveled if desired; as is standard construction in starter-motor drives.

The member 21 of the drive unit is associated with the starter-motor-driven shaft 18, 50 as by splines 23, so that it cannot turn relatively to said shaft but may be shifted along the shaft. This longitudinal shifting is always of the two members 20 and 21 as a unit, 55 for they are interlocked in any suitable way against relative axial movement other than is sufficient for clearance. This interlocking against relative axial movement may be obtained in any convenient way, as by having 60 the rear end of the member 20 telescoped within the forward end of the member 21, and interlocked against separation by a split retainer ring 24 suitably located in a circumferential groove on the inside of the hollow 65 open forward end of the member 21.

The two members 20 and 21 are connected by an overrunning clutch preferably of the type claimed in my aforesaid prior patent application in which the two members 20 and 21 have mating circular recesses 26 and 27 in 70 their abutting ends. A coiled clutch-spring 28 is located in these recesses, and extends across the transverse plane of separation between the two members 20 and 21 and into both recesses 26 and 27. The outer surface 75 of this clutch-spring 28 is in frictional cooperation with the internal surfaces of the recesses 26 and 27. In consequence, when there is a tendency to rotate the two members 20 and 21 in one direction with relation to 80 each other, the friction of the recess walls on the outer surface of the clutch-spring tends to unwind such clutch-spring and force the clutch-spring surface more tightly into engagement with the walls of the recesses 26 and 27, thus locking the two members 20 and 21 together against relative rotation in that direction; whereas when there is a tendency to rotate such two members 20 and 21 in the 85 other direction with relation to each other, the friction of the recess walls on the outer surface of the clutch-spring tends to wind up said clutch spring more tightly, and thus releases the two members 20 and 21 from the clutch-spring and so from each other and 90 permits relative rotation between said two members in that direction. The locking together of the two members 20 and 21 by the clutch-spring 28 is when the starter motor 16 is turning in the proper direction to start the 100 engine 10, or clockwise in Fig. 3, and the engine is resisting such turning, as by its friction and compression; while the releasing of the two members for relative rotation between them occurs when the speed of the shaft 18 is 105 less than the speed at which the pinion 22 is turned by the ring-gear 12 after the engine has started in operation under its own power; the coiled-spring clutch in the latter case permitting overrunning of the member 20 with 110 respect to the member 21.

For shifting the drive unit 20-21 axially, I provide a shifter fork 30, which has inwardly projecting pins 31 which project into a circumferential groove 32 in one of the 115 members 20 or 21; the groove 32 is probably most conveniently provided in the member 21, as illustrated. The shifter fork 30 may be hung on a suitable pivot 33, and is connected by a link 34 to the downwardly extending 120 arm of a bell-crank 35. The rearwardly extending arm of such bell-crank 35 lies beneath and normally substantially in contact with a pin 36 carried by a shifter switch 37.

This shifter switch, in the form shown, consists of a tube 38 slidably mounted in a casing 39 and carrying at its lower end a cross-connector 40 for connecting two switch contacts 41 and 42 which are connected by conductors 43 and 44 to the battery 17 and the 130

starter motor 16 in the usual way, the other terminals of such battery and starter motor being grounded. The head 45 at the upper end of the pin 36 lies within the tube 38, and 5 is held from downward movement out of said tube by an inturned flange 46 at the lower end of said tube; and a spring 47 lies within the tube 38 between the pin-head 45 and the upper end of such tube 38, so that by the 10 compression of the spring 47 the tube 38 may descend even though the pin 36 is held from descending. Normally the tube 38 and pin 36 move together; and the parts are so arranged and proportioned that when the tube 15 38 is depressed the cross-connector 40 does not engage the switch contacts 41 and 42 until after there has been sufficient movement of the tube 38 normally to produce meshing of the pinion 22 with the ring-gear 12. The 20 downward movement of the tube 38 and pin 36, and the meshing-producing movement of the drive unit 20—21, are opposed by a spring 48, which when the operator's heel is released from the shifter switch 37 acts to raise such 25 shifter switch and to withdraw the drive unit from mesh with the ring-gear 12. This spring 48 is shown, for example, as a tension spring acting on the depending arm of the bell-crank 35; but this is merely a convenient 30 arrangement for the spring, and not a necessary one.

In normal operation, the parts are in the position shown in Fig. 1 and in full lines in Fig. 2. The pinion 22 is out of mesh with 35 the ring-gear 12. This is the condition when all the parts are at rest, and also when the engine 10 is in normal operation.

When, with the engine 10 at rest, it is desired to start such engine, the operator steps 40 on the shifter switch 37. The resultant depression of the tube 38 and pin 36 acts to turn the bell-crank 35 against the spring 48, and to shift the drive unit 20—21 forward, or to the left in Figs. 1 and 2, to the dotted-line 45 position shown in Fig. 2. This produces meshing of the pinion 22 with the ring-gear 12; unless the pinion teeth and the ring-gear teeth happen to register substantially exactly so that the entry of the pinion teeth into the 50 spaces between the ring-gear teeth is prevented. In the latter case, the ends of the pinion teeth and the ring-gear teeth bear against each other, and the spring 47 is compressed to let the tube 38 descend even though 55 the pin 36 is held from descending. The bevels on the ends of the teeth tend to promote meshing of the teeth; and such bevels are desirably in the proper direction that their camming action on each other tends 60 to rotate the member 20 in the direction in which the spring 28 permits it to turn freely. At the last part of the downward movement of the shifter switch, the cross-connector 40 engages the switch contacts 41 and 42 to complete 65 the starter-motor circuit; whereupon

the starter motor starts at once to rotate. Ordinarily this starter-motor rotation does not start until after the pinion teeth and gear teeth are fully in mesh; but if the teeth of the pinion and ring-gear happen to have registered 70 so that such meshing has been prevented, the meshing occurs as soon as the starter motor has turned the pinion 28 half a tooth-pitch, as by that time the spring 47, which is stronger than the spring 48, will 75 have expanded to force down the pin 36 and move the drive unit forward as soon as the pinion teeth and the ring-gear teeth have been moved slightly out of line with each other. Thus the teeth of the pinion and ring 80 gear, as well as all the other parts, are prevented from receiving the shock which occurs in certain present-day drives, because the meshing of the teeth occurs before the pinion has gained any material amount of speed. 85

Upon the starting of the starter motor 16, with the teeth of the pinion and ring-gear already in mesh, or in mesh within half a tooth-space, power is transmitted from the starter-motor-driven shaft 18 and member 21 90 through the clutch-spring 28 to the member 20 in such a direction that the friction of the parts tends to unwind the clutch-spring 28. This locks the two parts 20 and 21 together; and the power thus received by the 95 member 20 is transmitted by its pinion teeth 22 to the ring-gear 12, to turn over the engine 10.

As soon as the engine 10 starts to operate under its own power, the ring-gear 12 starts 100 to rotate more rapidly than while it was being driven by the starter motor, and drives the pinion 22 and part 20 with correspondingly increased speed. In consequence, the member 20 runs ahead of the member 21; 105 which is permitted because this tendency to relative rotation between the parts 20 and 21 tends to wind up the clutch-spring 28 and thus to release it from such members to permit such relative rotation in that direction. 110 Ordinarily as soon as this occurs, the operator releases the shifter switch 37, whereupon the spring 48 raises such shifter switch and moves the drive unit to the rear (or to the right in Figs. 1 and 2) to the full-line position shown, to de-mesh the pinion teeth 22 from the ring-gear 12. However, if the operator fails to do this immediately, no harm ensues, because the interaction of the clutch-spring 28 with the recesses 26 and 27 permits 115 the free overrunning of the member 20 ahead of the member 21.

In case of a backfire of the engine 10 as it is being started, power is transmitted from the member 20 to the member 21 tending to 120 drive the starter motor 16 backward; for with this back drive of the member 20 upon a backfire there is the same clutch-spring-unwinding tendency to relative rotation between the members 20 and 21 as there is 125 130

when power is transmitted for said driving from the member 21 to the member 20. This may put a great strain on the parts, particularly on the starter motor. I may avoid this, 5 however, by making the cross-section of the clutch-spring 28 smaller, as is indicated in Fig. 5, so that it has less ability to transmit power. That is, I have found by experiment that by making the clutch-spring 28 of 10 smaller cross-section, its capacity to transmit power even in the spring-unwinding direction is thereby reduced; and, as a result, the capacity of the clutch spring to transmit power even in the spring-unwinding direction 15 may be reduced to a point below that which is reached upon a backfire of the engine, with the result that though the member 20 may turn backward the starter motor itself and its shaft 18 and the member 21 may continue 20 to rotate forward. This reduction in cross-sectional area of the clutch-spring 28 will depend upon its diameter, upon the size of the engine, and upon the power of the starter motor, and will vary with different installations. 25 Whether with or without the reduced cross-sectional area, it is not essential that the individual turns of the clutch-spring 28 should be square, although it is illustrated as square in Fig. 2, as such cross-section may 30 take other shapes as desired.

I claim as my invention:—

1. A starter drive, comprising a starter-motor-driven shaft, a power-receiving gear connected with an internal combustion engine, a pinion shiftable into and out of mesh with said power-receiving gear, a driving connection between said shaft and said pinion, said driving connection including an overrunning clutch, a switch for controlling 35 the circuit of the starter motor, and a yieldable pinion-shifting connection between said switch and said pinion whereby opening and closing of the switch produces shifting of the pinion.

45 2. A starter drive, comprising a starter-motor-driven shaft, a power-receiving gear connected with an internal combustion engine, a pinion shiftable axially into and out of mesh with said power-receiving gear, a driving connection between said shaft and said pinion, said driving connection including an overrunning clutch, a switch for controlling 50 the circuit of the starter motor, and a yieldable pinion-shifting connection between said switch and said pinion whereby opening and closing of the switch produces shifting of the pinion.

60 3. A starter drive, comprising a starter-motor-driven shaft, a member slidable thereon but rotatable therewith, a pinion slidable as a unit with said member, an overrunning clutch between said member and said pinion, a power-receiving gear connected with an 65 internal combustion engine and into and out of mesh with which said pinion is movable

by the sliding of said member, a switch for controlling the circuit of the starter motor, and a yieldable pinion-shifting connection between said switch and said member whereby opening and closing of the switch produces shifting of said member and pinion. 70

4. A starter drive, comprising a starter-motor-driven shaft, a power-receiving gear connected with an internal combustion engine, a member connected with said shaft 75 to rotate therewith, a pinion associated with said member, a coil-spring for clutching together said pinion and said member, said coil spring being in operative engagement with one of said parts and extending into an axial recess in the other of such parts so that it will expand to grip the walls of such recess when said pinion and said member tend to rotate relatively in a direction to unwind said spring, said member and said pinion being shiftable as a unit to move the pinion into and out of mesh with said power-receiving gear, and a pinion-shifting connection between said switch and said pinion whereby opening and closing of the switch 80 produces shifting of the pinion. 85

5. A starter drive, comprising a starter-motor-driven shaft, a power-receiving gear connected with an internal combustion engine, a member connected with said shaft to 90 rotate therewith, a pinion associated with said member, a coil-spring for clutching together said pinion and said member, said coil spring being in operative engagement with one of said parts and extending into an axial recess 95 in the other of such parts so that it will expand to grip the walls of such recess when said pinion and said member tend to rotate relatively in a direction to unwind said spring, said member and said pinion being shiftable as a unit axially of said shaft to move the pinion into and out of mesh with said power-receiving gear, and a pinion-shifting connection between said switch and said pinion whereby opening and closing of the switch 100 produces shifting of the pinion. 105

6. A starter drive, comprising a starter-motor-driven shaft, a power-receiving gear connected with an internal combustion engine, a member connected with said shaft to 115 rotate therewith, a pinion associated with said member, a coil-spring for clutching together said pinion and said member, said coil spring being in operative engagement with one of said parts and extending into an axial recess in the other of such parts so that it will expand

120 to grip the walls of such recess when said pinion and said member tend to rotate relatively in a direction to unwind said spring, said member and said pinion being shiftable as a unit to move the pinion into and out of mesh with said power-receiving gear, and a yieldable pinion-shifting connection between said switch and said pinion whereby opening and 125 closing of the switch produces shifting of the pinion. 130

closing of the switch produces shifting of the pinion.

7. A starter drive, comprising a starter-motor-driven shaft, a power-receiving gear connected with an internal combustion engine, a pinion shiftable into and out of mesh with said power-receiving gear, a driving connection between said shaft and said pinion, said driving connection including an overrunning friction clutch directly co-operating with said pinion, a switch for controlling the circuit of the starter motor, and a pinion-shifting connection between said switch and said pinion whereby opening and closing of the switch produces shifting of the pinion.

8. A starter drive as set forth in claim 4, with the addition that said helical clutch-spring is arranged to release its grip when the force between the two parts it connects exceeds a certain maximum less than that produced on the backfire of the engine.

9. A starter drive as set forth in claim 3, with the addition that the driving connection between said shaft and said pinion includes two associated parts arranged to transmit power from one to the other when the force between them in one direction does not exceed a certain maximum less than that produced on the backfire of the engine but to move relatively to each other without transmitting power both when the force between them exceeds such maximum in such one direction and when the force between them is in the opposite direction.

35 10. In combination, an internal combustion engine, a starter motor therefor, and a driving train for interconnecting said starter motor to said internal combustion engine, said driving train comprising two power-transmitting devices in series, one of said power-transmitting devices including two members and a helical spring interconnecting said two members and frictionally gripping both of them on curved surfaces and the other power-transmitting device including two members which can be moved into and out of engagement with each other, a switch for controlling the operation of said starter motor, and operating means connecting said switch with one of said two members for producing their engagement and disengagement when the switch is operated.

In witness whereof, I have hereunto set my hand at Indianapolis, Indiana, this 3d day of March, A. D. one thousand nine hundred and twenty-six.

WILLIAM CARLETON STARKEY.
